UNITED STATES PATENT OFFICE.

JOHN B. DYAR, OF DETROIT, MICHIGAN.

DESIGN FOR A RADIATOR.

SPECIFICATION forming part of Design No. 18,615, dated September 18, 1888.

Application filed June 8, 1888. Serial No. 276,535. Term of patent $\frac{3}{4}$ years.

To all whom it may concern:

Be it known that I, JOHN B. DYAR, a citizen of the United States, residing at Detroit, in the county of Wayne and State of Michigan, 5 have invented and produced a new and original Design for Radiators or Radiator-Loops, of which the following is the specification, reference being had to the accompanying drawings, forming a part thereof.

10 The invention consists in the design or configuration of the loop, by which, when a series of such loops are assembled together, the top of the radiator so formed simulates the top of a table.

15 In the accompanying drawings, Figure 1 shows a single loop embodying my invention, and Fig. 2 a radiator formed of a series of such loops.

An examination of the drawings will show that the loop A terminates in a flat top, B, 20 having a projecting edge, a, which, when a series of the loops are united, forms an edge on the top of the radiator resembling the top of a table.

What I claim as my invention is—

25 A design for a radiator-loop, consisting of the body portion having its upper end terminating in a flat top provided with a projecting edge, as shown.

JOHN B. DYAR.
